Attorney.

UNITED STATES PATENT OFFICE.

CHARLES RUPP, OF PHILADELPHIA, PENNSYLVANIA, ASSIGNOR TO J. S. THORN COMPANY, OF PHILADELPHIA, PENNSYLVANIA, A CORPORATION OF PENNSYLVANIA.

WINDOW FRAME.

Application filed May 20, 1922. Serial No. 562,325.

My invention is particularly applicable to metallic frames for what are known as double hung windows, including a jamb frame in which two sash frames are mounted to reciprocate parallel with each other.

As hereinafter described, my invention relates particularly to means for maintaining the sash frames in weather tight relation with the jamb frame, without interfering with the freedom of said sash frames for reciprocation. Such means include what I term a weathering strip which is, preferably, detachably connected with the jamb frame and has oppositely extending flanges overlapping and interengaging flanges upon the inner side of the outer sash frame and upon the outer side of the inner sash frame.

My invention includes the various novel features of construction and arrangement hereinafter more definitely specified.

In said drawings; Fig. I is a front elevation of a typical embodiment of my invention in a window frame including a jamb frame and two sash frames.

Fig. II is a vertical sectional view of the window frame shown in Fig. I, taken on the line II, II.

Fig. III is a fragmentary plan sectional view, taken on the line III, III in Figs I and II.

Fig. IV is a fragmentary plan sectional view, similar to Fig. III, but showing a modified form of my invention.

Fig. V is a fragmentary plan sectional view similar to Figs. III and IV, but showing another modified form of my invention.

Referring to Figs. I, II and III; the jamb frame 1 is formed of pressed sheet metal, for instance No. 16 gauge galvanized steel, and is adapted to be set in a suitable opening in a brick or other masonry wall, without the interposition of any wooden members. Said frame 1 includes the hollow head member 2 having the sash recess 3 and abutment flanges 5 and 6 respectively at the outer and inner edges of said head. Said frame 1 also includes the hollow sill 8 having the inner rail 9 and recessed sash seat flanges 10 and 11 and setting flanges 13 and 14.

As indicated in Fig. II, said frame 1 may be supported directly by its setting flange 13 resting upon the masonry wall 16, and said sill may be secured in rigid relation with said wall by the grouting 17 with

which the hollow of said sill is filled after said frame 1 is set. Said head 2 and sill 8 extend in substantially horizontal parallel relation, as indicated in Fig. I, and are rigidly connected by the oppositely counter- 60 part jambs 19 and 20.

Fig. III shows a cross section of said jamb 19 which, like the oppositely counterpart jamb 20, is a hollow structure formed of pressed sheet metal, for instance No. 16 65 gauge galvanized steel, and is conveniently composed of three primarily separate members viz, the outer channel 22, the intermediate brace web 23, and the inner face plate 24. Said channel 22 has recessed 70 flanges 27 and 28, respectively at the inner and outer faces thereof, adapted to fit within respective flanges 30 and 31 on said face plate 24. Said face plate 24 has the flanges 32 and 33, respectively at the outer and inner portions thereof, forming sash retaining and guiding rails. Said face plate 24 also has, intermediate of its width, the channel 35 to receive and hold the weathering strip 36, which is conveniently detachably 75 connected therewith by a series of screws 37 which extend through said strip 36 in engagement with said plate 24. Said strip 36 is preferably formed of sheet bronze and forms a parting rail between the outer sash 80 frame 38 and the inner sash frame 39.

As shown in Fig. III; said weathering strip 36 has two parallel webs respectively terminating in reversely and oppositely curved sealing flanges 41 and 42, which are 90 J-shaped to engage in their respective bights the similarly J-shaped sealing flanges 43 and 45 on said sash frames 38 and 39. That construction and arrangement are such as to baffle wind which otherwise might 95 penetrate the joints between said sashes 38 and 39 and said weathering strip 36, but permit said sashes to be slid in their respective runways in said recess between said rail flanges 32 and 33 in said face plate 24. 100

It may be observed that said weathering strip 36 is formed of pressed metal very much thinner than the metal of said sash frames 38 and 39; so as to be flexible and resiliently engage said sash frames and thus 105 not only practically hermetically seal the joints between said weathering strip and sashes, but also prevent rattling of said sashes.

As shown in Fig. II; said upper sash 110

frame 38 has its top rail 47 formed of a hollow pressed sheet metal member with the folded flange 48 which, in cooperation with the drawn steel hollow molding 49 retains the glass panel 50 which is imbedded in putty or other suitable cement 51 between said flange 48 and molding 49. Said sash frame 38 has the bottom meeting rail 53 which is a hollow pressed sheet metal member having the drip flange 54 which is adapted to shed rain. Said meeting rail 53 has the channel 55 formed therein to receive the lower edge of said glass panel 50 which is imbedded in cement 56 therein. Said meeting rail 53 also has the channel 58 with the sealing flange 59 having the lip 60 to facilitate its engagement with the sealing flange 61 on the top rail 62 of the sash frame 39. Said top rail 62 is a double channel formed of pressed sheet metal, with the inside flange 64 upturned, and the intermediate folded flange 65 extending downwardly to cooperate with the drawn steel molding 66 to hold the glass panel 67, which is imbedded in the cement 68 between said flange 65 and molding 66.

Said sash frame 39 also includes the bottom rail 70, which is a hollow pressed sheet metal channel having the upturned folded flange 71 which cooperates with the drawn steel molding 72 to hold the lower edge of said glass panel 67 between them, imbedded in the cement 73. The inner web 75 of said bottom rail 70 is turned outwardly to form the flange 76 which slides over said sealing flange 10 on said sill 8. The outer web 78, of said lower sash rail 70, is similarly turned outwardly to form the flange 79 to cooperate with the sealing flange 11 on said sill.

Therefore, it is to be understood that the construction and arrangement above described are such as to practically hermetically seal the sashes 38 and 39 not only at their junctions with said jamb frame, but at their junctions with each other.

It may be observed that the essential feature of the weathering strip 36 above described is that it includes oppositely projecting flanges which interengage with suitable flanges on the respective sash frames. Although the J-shaped cross section of said interengaged flanges, shown in Fig. III, has the advantage of resilient flexibility, such as to minimize the frictional engagement of the sashes in the window frame, and thus permit them to be freely operated with the minimum amount of friction; such construction of weathering strip is not sufficiently rugged for some buildings. Therefore, the high degree of flexibility which is characteristic of the structure shown in Fig. III may, in some instances, be sacrificed to afford more rugged constructions and arrangements, for instance, such as shown in Figs. IV and V.

Referring to the form of my invention shown in Fig. IV; the weathering strip 81 is similar to said weathering strip 36, except that it is double-L shaped instead of double-J shaped. The oppositely extending sealing flanges 82 and 83 of said strip 81, which are conveniently formed of double thickness of the metal by folding the latter, are parallel with the main web of said face plate 24 and adapted to respectively engage with the sealing flanges 85 and 86 on the respective sash frames 87 and 88. Said sash frames 87 and 88 are otherwise constructed and arranged like the sash frames 38 and 39 above described. It is to be understood that said weathering strip 81 is thus made less flexible than the weathering strip 36, but is sufficiently flexible and resilient to cooperate with and yieldingly engage said sash frames 87 and 88.

However, it is not necessary to have the weathering strip between the sashes resilient to have it perform the sealing function herein contemplated. For instance, a still more rugged construction and arrangement is shown in Fig. V, wherein the weathering strip 90, instead of being formed of pressed sheet metal, like the strips 36 and 81 above described, is formed of a hot rolled, preferably steel, angle member with oppositely extending L-shaped sealing flanges 91 and 92, which are adapted to cooperate with sash sealing flanges 85 and 86, such as described with reference to Fig. IV. Of course, in the construction shown in Fig. V; longer screws, 93, must be substituted for the screws 37 shown in Fig. III, to detachably hold the weathering strip 90 in rigid relation with the jamb frame 1.

It may be observed that in each form of my invention above described, a weathering strip is provided extending as a parting strip between the sashes and having sealing flanges extending transversely to the plane of the window frame and sashes constructed and arranged for resilient sliding engagement with sealing flanges upon said sashes and, in the form of my invention shown in Fig. III, such sliding engagement is effected in respective planes which are obliquely transverse to the plane of said frame and sash and to each other.

Therefore, I do not desire to limit myself to the precise details of construction and arrangement herein set forth, as it is obvious that various modifications may be made therein, without departing from the essential features of my invention, as defined in the appended claims.

I claim:

1. In a window frame, the combination with a jamb frame member formed of sheet metal including a hollow guide rail and a sash frame member including a resilient sheet metal member adapted to slide in said

jamb member against said guide; of means constructed and arranged to substantially hermetically seal the joint between said sash and jamb members, including a laterally extending resilient sheet metal sealing flange on said sash member and a weathering strip, supported by said jamb member, having a laterally extending sealing flange, in inwardly spaced relation with said jamb and interengaged with said sealing flange on said sash member; said sealing flanges having surfaces in sliding contact in a plane transverse to the plane of said sash.

2. In a window frame, the combination with a jamb frame member and two sash frame members adapted to slide in said jamb member, in parallel relation with each other;

of means constructed and arranged to substantially hermetically seal the joints between said sash and jamb members, including opposite laterally inwardly extending, J-shaped, sealing flanges on said sash members and a resiliently movable weathering strip, having opposite laterally outwardly extending J-shaped sealing flanges, interengaged with said sealing flanges on said sash members; said sealing flanges having surfaces in sliding contact in a plane transverse to the plane of said sash.

In testimony whereof, I have hereunto signed my name at Philadelphia, Pennsylvania, this 17th day of May, 1922.

CHARLES RUPP.
